UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

FLUID COMPRESSOR.

Application filed February 9, 1920. Serial No. 357,132.

My invention relates to a fluid compressor, the principal objects of my invention being to generally improve upon and simplify the construction of the existing and 5 generally used forms of fluid compressors; and to provide a relatively simple, easily operated, and effective structure wherein a body of liquid confined in a chamber between a pair of rotors, one of which is eccentrically disposed with respect to the other, is 10 effective in rapidly compressing to relatively high degrees of pressure, air and like gaseous fluids.

Further objects of my invention are, to 15 provide simple and efficient means for controlling the action of the liquid contained in the chamber between the rotors; to provide means for effectively controlling the air or other fluids compressed in the machine; to provide simple means which will 20 act automatically when the speed of the compressor is retarded to seal the housing of the compressor against the escape of fluids; to provide improved and effective 25 means for lubricating the bearings of the compressor; to provide for the maintenance of the proper amount of liquid in the chamber between the rotors; and to provide 30 simple and effective means for disseminating any heat which may develop in the operation of the compressor.

My invention is characterized by the use 35 of a pair of suitable rotors, one eccentrically disposed within the other, so as to form an eccentric chamber between the annular wall of the external rotor and the periphery of the internal rotor, and to maintain within 40 said chamber a body of simple or compound liquid which, while the compressor is in operation, will by centrifugal forces, be moved outwardly against the annular wall of the external rotor, thereby forming 45 practically an annular body of liquid which moves with both rotors.

The peripheral portion of the eccentrically disposed internal rotor will, in operation, move into the annular body of liquid, and as said internal rotor is provided in its periphery with pockets, any air or like fluids 50 contained therein will be compressed and in such condition discharged from the internal rotor and delivered to a suitable storage chamber.

The flexibility or density of the annular

body of liquid may be varied as desired, or 55 as conditions may require. A fixed density may be attained by a given speed and varying the radius, or by maintaining the same radius and varying the speed; or the peripheral speed may be maintained constant in 60 both cases.

To attain best results, the two rotors should be driven at approximately the same peripheral speed, and in the same direction.

Heretofore, in the compression of fluids 65 it has generally been the practice to utilize solid surfaces which approach each other in effecting the compression of air or gases, but in my improved apparatus, a flexible or mobile surface cooperates with a fixed or 70 solid surface, and by such arrangement, the flexibility and efficiency of the device is greatly increased and at the same time the leakage of fluid pressure is minimized.

With the foregoing and other objects in 75 view, my invention consists in certain novel features of construction and arrangement of parts, hereinafter more fully described and claimed, and illustrated in the accompanying drawings, in which—

Figure 1 is a vertical section taken 80 through the center of a fluid compressor of my improved construction.

Figure 2 is a vertical section taken approximately on the line 2—2 of Figure 1.

Figure 3 is a vertical section taken approximately on the line 3—3 of Figure 1.

Figure 4 is a vertical section taken approximately on the line 4—4 of Figure 1.

Figure 5 is a vertical section taken approximately on the line 5—5 of Figure 1.

Figure 6 is a longitudinal section of a modified form of my improved compressor.

Figure 7 is a cross section taken approximately on the line 7—7 of Figure 6.

Figure 8 is an enlarged detail section illustrating a part of the journal bearing oiling system utilized in connection with the form of compressor illustrated in Figures 6 and 7.

Figure 9 illustrates a modified form of 100 the discharge valve.

Figure 10 illustrates a further modified form of the discharge valve.

Figure 11 illustrates a modified form of 105 the overflow valve.

Fig. 12 is a sectional view of the internal and external rotors of the compressor and showing the mobile body that occupies the

chamber between said rotors and which cooperates with the internal rotor in effecting the compressing action.

Figure 13 is a sectional view showing a construction wherein the external rotor is cooled by air currents drawn into and through the outer housing of the compressor.

Referring by numerals to the accompanying drawings, which illustrate a practical embodiment of my invention, 10 designates the annular wall of the outer housing or shell of the compressor, and formed integral with one side of this annular wall is a plate 11 with the central portion of which is formed integral an outwardly projecting tubular bearing 12. The opposite end of the annular wall is closed by a removable plate 13 in the center of which is formed an outwardly projecting tubular bearing 14, the same being in horizontal alignment with bearing 12. The bearings 12 and 14 are preferably provided with suitable bushings 15 and journaled therein is a shaft 16, that is connected to suitable driving means, preferably a motor. That portion of the shaft which extends through the casing or housing formed by the walls 10, 11 and 13 is provided with an axially disposed chamber 17, its outer end being closed by a screw plug 18.

Formed integral with the plates 11 and 13 are inwardly projecting circular lugs 19 and 20, respectively, the same being eccentrically disposed with respect to the axes of the bearings 12 and 14 and mounted for rotation on these eccentrically disposed lugs is a container or housing that comprises an annular wall 21 and side walls 22 and 23, the latter being removably connected to the annular wall 21 in any suitable manner.

To minimize the wear between the external rotor or housing comprising the walls 21, 22 and 23, I prefer to arrange on the eccentric lugs 19 and 20, loose bushings 19^a and 20^a, respectively, of suitable wear resisting metal.

Fixed on shaft 16 within the external rotor comprising the walls 21, 22 and 23 is the inner rotor of the compressor, the same comprising a substantially annular block 24 that is provided in its periphery with a plurality of depressions or pockets 25. The axes of the circular lugs 19 and 20 are elevated with respect to the axis of shaft 16 and by virtue of this arrangement and the fact that inner rotor 24 is fixed directly to said shaft 16, the pocketed periphery of said inner rotor is positioned immediately adjacent to the inner periphery of the annular wall 21 of the external rotor at the bottom of the latter, and the space A between the external periphery of the internal rotor and the inner periphery of the external rotor gradually increases toward the top of the structure. (See Fig. 4).

The side face of the inner rotor 24 adjacent to the plate 23 is recessed to form an annular chamber 26 and removably secured to this side of said inner rotor is a plate 27 which closes said annular chamber 26. The peripheral portion of this plate 27 forms the side wall for the pockets 25 and formed in said plate adjacent to its periphery and within each pocket is an arcuate slot 28. Each of these slots or ports 28 communicates with a radially disposed passageway 29 that is formed in plate 27, and the inner end of each passageway has communication with the annular chamber 26 by means of a port 30, the latter being formed through the inner portion of plate 27. Formed through the inner portion of plate 27 or that portion which is adjacent to the hub of the inner rotor 24 is a series of ports 31, the same being preferably spaced at equal distances apart and adapted to communicate as the inner rotor operates with a passageway 32 that is formed through the eccentric hub 20 and wall 13. Connected to the outer end of this passageway 32 is a pipe 33 by means of which the air or fluid to be compressed is delivered to the compressor.

The side of rotor 24 that is adjacent to plate 22 is recessed to form an annular chamber 34 and removably positioned on this side of the rotor and closing said chamber is a plate 35. A port 34^a establishes communication between chamber 34 and chamber 17 in shaft 16. Each pocket or recess in the rotor is connected to the annular chamber 24 by a substantially U-shaped passageway 36, the same being radially disposed and constituting a valve or trap, the operation of which will be hereinafter more fully described.

Formed in plate 35 are two or more radially disposed overflow ports or passageways 37, the inner ends thereof communicating with the outer portion of annular chamber 34 and the outer ends being extended through the inner portion of plate 35 to the outer face thereof so as to communicate with that portion of annular chamber A that is immediately below the eccentric lug 19. (See Fig. 1.)

Formed through the wall 22 and substantially in the same horizontal plane with the arcuate ports 28 when the same are at their highest point of travel is a passageway 38 and formed therein is a valve seat upon which normally rests a spring-pressed valve 39, the stem of which is radially disposed with respect to the axis of the compressor. The spring behind this valve is relatively light so that when the outer rotor of the housing comprising the parts 21, 22 and 23, reaches a certain speed, the valve will by centrifugal action be raised from its seat, thereby opening the passageway 38.

Projecting inwardly from annular wall 10

between the plates 11 and 22 is an annular flange 40 and operating within the space between this flange and wall or plate 11 is a series of radially disposed blades 41 that are carried by a hub that is mounted on the hub of the outer rotor and said blades being for the purpose of circulating a cooling medium that fills the space between the outer fixed housing of the compressor and the external rotor comprising the parts 21, 22 and 23. This cooling medium is delivered to the chamber within the outer fixed housing through a pipe 42 that is tapped into plate 13 and said cooling medium discharges from the outer housing through a pipe 43 that leads downward from the space occupied by the blades 41.

Secured in any suitable manner to the plate 11 of the housing of the compressor is a secondary housing 44 and formed in the outer wall thereof is a centrally arranged aperture 45 that accommodates the shaft 16. Secured in any suitable manner to the outer plate of the housing 44 around the opening 45 therein is an inwardly projecting collar 46 and carried by the inner end thereof is a disk 47. Fixed in any suitable manner on the end of bearing 12 that projects into the chamber within the auxiliary housing 44 is a disk 48 that has approximately the same diameter and thickness as the disk 47.

Fixed on the shaft 16 between the disks 47 and 48 is a pair of disks 49 that are spaced a slight distance apart to form an air chamber 50. Radially disposed ports 51 are formed in the shaft 16 and establish communication between the chamber 17 in said shaft and the space 50 between disks 49. The diameters of the disks 49 are slightly greater than the diameters of the disks 47 and 48, and secured in any suitable manner to the peripheries of said disks are the inner portions of rings 52 which overlie the peripheries of the disks 47 and 48 and carried by said rings are ring plates 53, which latter lie outside of and are spaced apart from the outer portions of disks 47 and 48.

The inner peripheries of the ring plates 53 terminate adjacent to the collar 46 and bearing 12, and by virtue of this construction, the outer portions of the disks 47 and 48 occupy the narrow annular chambers between the ring plates 53 and outer portions of the disks 49, and to prevent the escape of air from the chamber within auxiliary housing 49 through the spaces between the various plates, and disks, the annular chambers in which the peripheral portions of the disks 47 and 48 operate are partially filled with a suitable sealing liquid which, when the compressor is in operation, is thrown outwardly by a centrifugal force

so as to occupy the outer portions of said annular chambers.

Secured in any suitable manner to the outer face of the outer plate of the auxiliary housing 44 is a ring 54, the inner portion of which is spaced apart from the outer plate of said auxiliary housing, and formed on the inner face of this ring and upon the outer face of the outer plate of said auxiliary housing are flat annular bearing faces 55. Fixed on shaft 16 and positioned in the space between the ring 54 and the adjacent plate of the auxiliary housing is a relatively thin metal disk 56, the periphery of which is slightly widened to form a ring 57, and the latter being adapted to make contact with either one of the bearing faces 55. This disk 56 is slightly dished or concavo-convex so that when the compressor is at rest, the ring 57 will make contact with one of the bearing faces 55, thereby forming a seal to prevent the escape of air or liquid from the compressor.

When the compressor is in operation, the thin metal disk 56 will by centrifugal forces tend to straighten out or occupy a plane at direct right angles to the axis of the shaft 16, and thus the ring 57 will be moved to and maintain a position midway between the bearing faces 55, as illustrated in Figure 1. Leading from the chamber within the auxiliary housing 44 to a suitable container or storage tank is a compressed fluid conveying pipe 58.

The operation of my improved fluid compressor constructed as heretofore described, is as follows:

As shaft 16 is driven at a comparatively high rate of speed, the body of simple or compound liquid in the eccentric chamber A between the internal and external rotors will by centrifugal force be thrown outwardly against the inner face of annular wall 21 of the external rotor so as to form a substantially annular mobile or yielding body and when a certain speed of rotation has been reached, the external rotor with the annular body of liquid against the inner surface of wall 21 will rotate with the internal rotor 24, and which latter is fixed to shaft 16. By virtue of the fact that the internal rotor is eccentrically disposed within the external rotor, the periphery of said internal rotor will, during operation, pass into the annular body of liquid in the chamber A and as a result, air, gas or other fluid which may be trapped in said pockets, will be compressed and forced through the U-shaped traps or ports 36 into the chamber 34.

As the peripheral portion of the internal rotor travels through the upper portion of the chamber A, the body of liquid will gradually uncover the ports 28 at the outer ends of passageways 29, and as such action occurs

the partial vacuum established in the pockets or recesses as a result of the outward movement of the liquid will cause air, gas or other fluid to be drawn into the compressor 5 through inlet pipe 33, passageway 32, through ports 31, which latter successively register with the inner end of passageway 32 and the air from the chamber 26 will pass through the passageways 29 and discharge 10 from the ports 28 as the liquid within chamber A uncovers said ports.

As the internal rotor moves downward and through the lower portion of the compressor, it will force its wall into the annular body of liquid contained in said chamber with the result that the air trapped in the pockets or depressions will be compressed and forced through the U-shaped passageways 36 to chamber 34. From this chamber 15 the compressed air or other fluid will discharge through ports 34 into the chamber 17 in shaft 16 and from this latter chamber, the compressed fluid will pass outwardly through ports 51 to chamber 50 between the disks 49 and from said chamber, compressed fluid will pass through outlet pipe 58 to a suitable container or storage tank.

The depth of the mobile body within 30 chamber A will be regulated by the position of the outlet port 38 for when the compressor is in operation, valve 39 will be moved off its set by centrifugal force and any surplus of liquid within chamber A 35 will pass outwardly through port 38 and will gravitate to the bottom of the chamber within the housing comprising the parts 10, 11, and 13. The U-shaped passageways 36 constitute traps or liquid valves to control 40 the discharge of the compressed fluid from the pockets 25 and there is a certain amount of liquid contained in chamber 34 and in the legs of the U-shaped passageways.

When the compressor is in operation, 45 centrifugal force will cause this liquid to move to the outer portion of the chamber 34 and said liquid will also fill the U-shaped passageways 36. As the fluid trapped in the pockets is compressed to the highest degree 50 at the bottom or lower portion of the compressor, said fluid will pass through the liquid traps into the annular chamber 34 and in so doing the liquid therein will be displaced and the compressed air will finally 55 pass through the ports 34 into the chamber 17 within the shaft 16. Should an excess of liquid accumulate in these U-shaped passageways and chamber 34, such excess will 60 find exit through the passageways 37 and discharge therefrom into the chamber A between the internal and external rotors.

The U-shaped passageway 36 formed in the internal rotor when combined with the chamber 34 forms in cross section a 65 substantially reversed N-shaped conduit,

the first leg of which discharges the compressed air or fluid at a point near the axis of rotation, whereas the last leg opens into the bottom of the compressing pocket, the junction of the first leg and diagonal 70 passage or conduit forming a liquid seal or trap.

It will be noted that the concentric mounting of the internal rotor will appropriately open and close the inner end of the 75 overflow discharge passage 37 from the pocket and which is located relatively close to the axis of rotation. By referring to Figure 1 it will be seen that the inner end of the discharge conduit 37 above the shaft 80 16 is closed by the hub 19, whereas the inner end of the discharge conduit 37 at the lower portion of the internal rotor and below shaft 16 is open, the same having passed in its revolution beyond the closing zone of the hub 19 and bushing 19^a, the eccentric relation of these parts being such that the inner ends of ports 37 start to open when reaching or approaching the lower half of the revolution and are fully closed when reaching or approaching the upper half of the revolution, they remaining open or partially open during the lower half of the revolution and being nearly closed during the upper half of the revolution. This prevents back pressure in the chamber in which the internal rotor operates from exercising a back lash in the discharge conduits from the pockets when said pockets are receiving a fresh supply of fluid, or air (at atmospheric pressure) to be compressed.

It will be further noted that the inlet ports 28 enter the outer portions of the pockets and above the bottoms thereof so that these inner ports are sealed by the outer ring of liquid before the final compression of fluid in the pockets.

During the operation of the compressor, any heat developed as a result of the high speed attained by the rotors and the action of compressing the fluid will be disseminated by the cooling medium that enters the fixed housing of the compressor through supply pipe 42 and discharges through pipe 43, and which cooling medium is circulated within the housing by the blades 41. The disks 47, 48 and 49 and the ring plates 53, together with sealing liquid contained in the narrow chambers in which the disks 47 and 48 are positioned, cooperate to provide an effective seal to prevent the escape of fluid pressure past the journal bearing 12.

During the operation of the compressor the sealing liquid will be maintained in annular form in the outer portions of the chambers between the disks 49 and the ring plates 53, thus wholly covering the peripheral portions of disks 47 and 48, and as a result, this compressed fluid passing into the chamber enclosed by auxiliary housing 100

44 will be prevented from escaping from said chamber and all of said compressed fluid will discharge through outlet 58.

When the compressor is stopped, the sealing liquid will by gravity pass to the lower portions of the chambers occupied by the disks 47 and 48, and the pressure within housing 44 will then pass outwardly through ring 46 and its action against the disk 56 10 will force the ring 57 on the edge of said disk against the outer one of the seats 55, thereby maintaining the pressure that has been built up in the compressor.

When the compressor is again started, 15 centrifugal force will cause the disk 56 to move into a straight radial plane with the peripheral ring 57 out of engagement with the seats 55.

In Figure 9 I have illustrated a modified 20 form of the liquid sealed fluid outlet valve 36, this modified construction involving a substantially U-shaped passageway 59, one leg of which is connected to the adjacent pocket 25 of the internal rotor and the outer 25 end of the opposite leg of said passageway communicating with a short arcuate port 60 which communicates with the chamber 34 within the internal rotor. This liquid sealed outlet valve is radially disposed with 30 respect to the axis of the internal rotor and lies substantially parallel with its side faces, whereas in the construction previously described, the liquid sealed valves or outlet ports 36 are disposed transversely of said 35 internal rotor.

In Figure 10 I have illustrated a modified construction wherein a weighted spring-pressed valve is utilized for normally closing the fluid outlet ports from the pockets 25.

40 In this construction, an outlet port in passageway 61 is formed through the periphery of the internal rotor and the lower end of this port is provided with a seat which is normally closed by a valve 62. This valve is 45 carried on the end of a short lever or arm 63 that is fulcrumed on a bracket 64, the latter being disposed within the chamber 34 in the internal rotor and the free end of the arm or lever 63 carrying an adjustable weight 65. 50 Mounted on the fulcrum of this lever is a spring 66 which tends to normally maintain the valve 62 upon its seat.

When the internal rotor reaches a certain 55 speed, centrifugal forces will move weight 65 toward the periphery of the internal rotor, thereby swinging the arm or lever 63 upon its fulcrum, and consequently unseating valve 62 to permit the discharge of compressed fluid to pass through outlet 61.

60 In Figure 11 I have illustrated a modified form of control for the overflow of liquid from the chamber A through the outlet passageways 37, said modified construction comprising the fulcrumed lever 67 the same 65 carrying a valve 68 that is adapted to close

the overflow passageway 37 and the free end of said lever carrying a float 69 which, when the liquid reaches a certain height or volume will move the float outwardly, thereby closing valve 68.

In Figures 6, 7 and 8 I have illustrated a modified construction of the compressor wherein the external rotor is positively driven by the internal rotor, and this modified construction also including means for lubricating the bearings for the compressor shaft. In this construction, the internal rotor is provided on one of its side faces with a disk 70, the periphery of which is provided with teeth 71 that are adapted to engage 75 with teeth 72 that are formed on the inner periphery of a ring 73, and the latter being fixed to the inner face of one of the side plates of the external rotor. The disk 70 rotates with the shaft 16 and the internal 80 rotor carried thereby, and consequently transmits rotary motion to the external rotor. In this construction, the bushings 15 which constitute bearings for the shaft 16 extend outwardly into suitable oil pockets 74 that 85 are formed in the bearings on the side plates of the outer housing, and formed in the inner or bearing faces of these bushings are longitudinally disposed oil ducts 75. The tops of these bushings are cut away as designated by 76 and which cut-away portions communicate with the ducts 75, and loosely arranged upon the shaft 16 and positioned in these cut-away portions 76 are rings 77 which depend into the adjacent oil pockets 90 95 100

74. Thus as the shaft 16 rotates, oil is carried upwardly by the rings 77 and this oil will be distributed onto the shaft bearings through the oil ducts 75.

For the purpose of lubricating the bearings for the external rotor on the eccentrically disposed lugs 19 and 20, an annular oil pocket such as 78 is formed in the inner face of the side wall of the outer housing, around the eccentrically disposed lug thereupon, and extending into this pocket from the adjacent hub on the external rotor is an annular flange 79 upon which is loosely mounted a ring 80, and which latter as it rotates will carry oil from the lower portion of the pocket 78 to the upper portion thereof. The adjacent bushing such as 19^a is provided with a series of radially disposed oil ducts 81, the same communicating with longitudinally disposed ducts such as 82 which lead 110 115 120 back to the adjacent pocket 78. (See Fig. 8).

In Figure 13 I have illustrated a construction wherein the heat developed during the operation of the compressor is disseminated 125 by means of air currents drawn into and through the outer housing of the compressor, and to effect this circulation of air, the external rotor is provided, preferably on its periphery, with projections 83 in the nature of 130

vanes which, when the compressor is in operation, are effective in drawing air into the outer fixed housing, and the latter being provided with suitably located openings 5 such as 84 to permit the circulation of cooling air therethrough.

A fluid compressor of my improved construction is relatively simple, can be economically operated by virtue of the fact that 10 very little power is required for driving the rotors, and by utilizing a mobile body in a chamber between two rotors, air, gas or other fluids can be very easily and quickly compressed to relatively high degrees of 15 pressure.

It will be readily understood that minor changes in the size, form and construction of the various parts of my improved fluid compressor can be made and substituted for 20 those herein shown and described, without departing from the spirit of my invention, the scope of which is set forth in the appended claims.

I claim:

- 25 1. In a fluid compressor, an external rotor and an internal rotor, the latter comprising a body portion and two head portions secured in position at the sides thereof, said head portions being formed with inlet and 30 discharge ducts, and said body portion being formed with a continuation of said discharge duct.
2. A compressor of the type described comprising the combination of an external 35 rotor, an internal rotor enclosed thereby and provided with peripheral pockets having reversed N-shaped liquid sealed overflow passages leading into the chamber of the external rotor, and a centrifugally operated 40 valve carried by the external rotor for controlling a discharge conduit from said chamber.
3. A compressor of the type described comprising the combination of an external 45 rotor, an internal rotor enclosed thereby and provided with peripheral pockets having reversed N-shaped liquid sealed overflow passages leading into the chamber of the external rotor, and a centrifugally operated 50 valve carried by the external rotor for controlling a discharge conduit from said chamber, there being a radially disposed spring 55 for opposing said centrifugally operated valve.
4. The combination of a stationary housing, an external rotor arranged therein an internal rotor, a series of blades carried by said external rotor, and an annular flange carried by the stationary housing and extending between the external rotor and said 60 blades, said flange forming a collecting chamber, and a discharge pipe leading from said chamber.
5. The combination of a stationary housing 65 having an inlet and an outlet for a cool-

ing liquid, a rotor, blades carried by said rotor, and an annular flange in said housing between said blades and said rotor, said flange being also located between the inlet and outlet openings for the cooling liquid. 70

6. In a fluid compressor, the combination of an internal rotor, an external rotor wholly enclosing and sealing said internal rotor, a casing completely enclosing said external rotor, a hollow shaft journaled in said casing and supporting said internal rotor, said external rotor being provided with suitable liquid and said internal rotor having peripheral pockets adapted to be sealed by said liquid whereby the fluid trapped in said pockets is compressed by said liquid and forced therefrom, said internal rotor being provided with an intake chamber closed to the atmosphere, an inlet connection leading through said casing into said intake chamber, inlet ducts leading from said chamber and opening into each of said pockets at the highest point thereof centrifugally disposed outlet ducts formed in said internal rotor and leading from the bottom 90 of each pocket to said pressure chamber, communicating openings formed radially in said internal rotor and said shaft and connecting the pressure chamber of said internal rotor with said hollow shaft, and discharge 95 connections communicating with said hollow shaft for conveying away the compressed fluid.

7. In a fluid compressor, the combination of a housing, a hollow ported shaft journaled therein, an external rotor, an internal rotor fixed on said shaft and journaled on bosses formed on said housing, said shaft and said internal rotor being eccentrically disposed relative to said housing and 105 to said external rotor, a mobile body in said external rotor, said internal rotor being provided in its periphery with pockets in which the fluid is trapped and compressed by said mobile body, discharge ducts leading from the bottom of each pocket into a pressure chamber formed in said internal rotor, communicating ports formed in said internal rotor and said shaft for conveying the compressed fluid from said pressure chamber to 110 said shaft, a casing secured to said housing and having a pressure chamber in communication with said hollow shaft, a discharge connection leading from said pressure chamber, means for providing a liquid seal between the atmosphere and said pressure chamber during the operation of the compressor, and a flexible plate operable by the pressure in said chamber for sealing said chamber to the atmosphere when the compressor is idle. 115

8. In a fluid compressor, the combination with a housing, a mobile body therein, a shaft eccentrically journaled relative to said housing, an internal rotor fixed on said shaft, 120

- an external rotor loosely arranged within said housing and completely enclosing said internal rotor, said housing completely enclosing said external rotor, said internal 5 rotor being provided in its periphery with pockets in which the fluid is trapped and compressed by said mobile body, inlet ducts formed in said internal rotor and opening into each pocket at the highest point thereof, 10 liquid seal discharge ducts formed in said internal rotor leading from the bottom of each pocket into a pressure chamber formed in said internal rotor, an intake connection communicating through said housing with 15 said inlet ducts, a discharge connection communicating with said shaft, said shaft being provided with peripheral ports for permitting the discharge of the compressed fluid from said internal rotor through said shaft 20 into said discharge connection, an inlet connection leading into said housing, and an outlet connection leading from said housing for circulating therethrough a cooling medium.
9. A compressor comprising an outer 25 rotor arranged to contain a liquid, an inner rotor within the outer rotor arranged to receive rotative impetus from the liquid within the outer rotor when the outer rotor is rotated, wells in the periphery of the inner 30 rotor, passages through the inner rotor for conducting air into the space between the rotors, passages through the inner rotor from said wells for conducting air from said wells, and means for maintaining a liquid seal at 35 the outer side of the inner rotor for the outer ends of said last named passages.

In testimony whereof I hereunto affix my signature this 6th day of February, 1920.

JOHN O. CARREY.
